GARMENT HANGER MACHINE

Francis B. Todd, Attalla, Ala.

Application March 24, 1938, Serial No. 197,789

13 Claims. (Cl. 140—71)

My invention relates to wire forming machinery and more particularly contemplates the provision of a machine for forming wire garment hangers.

My invention further contemplates improvements in a machine of this kind whereby a large number of hangers may be formed per minute without causing excessive vibration of the parts and breakage of the parts.

10 My invention further contemplates the provision of a forming machine designed to produce a better looking hanger and one having greater strength.

My invention embodies other novel features, 15 details of construction, and arrangement of parts which are hereinafter set forth in the specification and claims and illustrated in the accompanying drawings, forming part thereof, wherein:

20 Fig. 1 is a plan view of my improved machine;

Fig. 2 is a fragmentary plan view of the feed carriage employed for carrying the wire blank into engagement with the forming plate, and 25 showing the feed carriage in its inoperative position;

Fig. 3 is a view similar to Fig. 2, showing the inward position of the feed carriage with respect to the forming plate;

30 Fig. 4 is a transverse sectional view of the feed carriage, showing the fingers employed for centering the wire blank;

Fig. 5 is a detail sectional view of the cam employed for moving the feed carriage;

35 Fig. 6 is a detail sectional view of the shoulder forming mechanism, showing same in its forming position;

Fig. 7 is an enlarged fragmentary view showing the manner in which the forming dies act 40 with the form plate to form the shoulder portion of the hangers;

Fig. 8 is an enlarged fragmentary view of the inner ends of the forming dies and a portion of the form plate;

45 Fig. 9 is a detail sectional view taken along the line IX—IX of Fig. 8, showing the forming dies engaging the ends of the wire blank to center same;

Fig. 10 is a view similar to Fig. 9, showing the 50 forming dies in their inward position;

Fig. 11 is a fragmentary detail view of the twister mechanism, showing the means employed for rotating the twister head for twisting the ends of the wire blank together prior to the 55 hook forming operation.

Fig. 12 is a sectional detail view showing the means employed for moving the twister head into and out of engagement with the ends of the wire blank;

Fig. 13 is a detail elevational view of the twister head;

Fig. 14 is a front view of the twister head;

Fig. 15 is a fragmentary plan view of the hook forming mechanism;

Fig. 16 is a sectional view taken along the 10 line XVI—XVI of Fig. 15, showing the hook forming mechanism;

Fig. 17 is a detail sectional view of the hook forming mechanism at the completion of the hook forming operation;

Fig. 18 is a detail sectional view of the cam and lever means employed to move the hook forming mechanism into and out of engagement with the work;

Fig. 19 is a detail sectional view showing the 20 work discharge mechanism; and

Fig. 20 is a detail view showing the type of wire hanger formed on my machine.

Referring now to the drawings for a better understanding of my invention, I show a machine 25 comprising a frame 11 provided with bearing brackets 12 secured at the corners thereof to receive the shafts 13, 14, 15, and 16. Bevel gears 17 and 18 are secured at the ends of the shaft 13 for engagement with bevel gears 19 and 20, 30 respectively, mounted on the shafts 14 and 15, respectively. A bevel gear 21 is secured on the shaft 15 to drive the bevel gear 22 secured on the end of the shaft 16. These shafts are driven by means of a gear 23 mounted on the shaft 13 35 and from any suitable source of power (not shown).

Feed carriage mechanism

Referring now more particularly to Figs. 1 to 40 5, inclusive, I show a form plate 26 which is secured in a horizontal plane to the bottom of a cross frame member 27 by means of screws 28. The ends of the cross frame member being secured to the frame 11. A feed carriage 29 is 45 mounted for reciprocation in front of the form plate 26 by means of guide rods 31 which are mounted in bearings 32, provided on the frame 11, and bearings 33 provided on the cross frame member 34.

The feed carriage 29 is provided with an arm 36 which carries a roller 37 at its end for engagement with a cam 38 secured on the shaft 16. A bearing 39 is mounted on the frame 11 to receive the arm 36. A pair of feeder arms 41 55

are employed to position the wire blanks, one at a time, between the feed carriage 29 and the form plate 26. As these feeder arms form no part of the present invention a further description of the construction and operation of same have been reserved for another application. A pair of fingers 43 are provided at each end of the feed carriage to carry the wire blanks 42 from the feeder arms to the form plate; and a pair of forming members 44 are provided on the feed carriage to act with the form plate to form the wire blanks and to hold same against displacement throughout the following forming operations.

15 A pair of forming arms 46 are pivotally mounted on the under side of the feed carriage 29 and provided with upturned fingers 47 for engagement with the ends of the wire blanks to wrap same around the ends of the form plate 26 as the feed carriage moves forwardly. The arms 46 are actuated by means of connecting links 48 which have their one ends pivotally connected to the arms and their other ends slotted at 49 to receive and engage pins 51 mounted on the frame 11. An adjustment screw 52 is provided at the outer ends of the connecting links; and the inner ends of the connecting links are connected by a tension spring 53.

30 Shoulder forming mechanism

Referring now to Figs. 1 and 6 to 10, inclusive, I show a pair of shoulder forming arms 56 and 57 mounted for reciprocation in bearings 58 and 59, respectively, secured to the inner sides of the frame 11. Rollers 61 and 62 are provided on the outer ends of the arms for engagement in cam slots 63 and 64 formed in the cams 66 and 67, respectively. The cam 66 is secured on the shaft 14 and the cam 67 is secured on the shaft 15. Forming dies 68 and 69 are secured on the inner ends of the forming arms and are preferably adjustably mounted thereon by means of screws 71.

The upper end of the forming die 68 is formed with a projecting centering lug 72; and the lower end of the die 69 is formed with a projecting centering lug 73. Slots 74 and 76 are formed in the ends of the dies 68 and 69, respectively, and at the base of the centering lugs to receive the ends of the wire blanks. The forming dies act with the form plate 26 to form the shoulder portion of the hangers and act with a tongue portion 77 on the form plate to cause the free ends of the wire blanks to project rearwardly in a horizontal plane and in parallel relationship.

55 Twisting mechanism

Referring now to Figs. 1 and 11 to 14, inclusive, I show a twisting mechanism comprising a shaft 81 provided with a twister head 82 and journaled in bearings 83 and 84. The shaft is moved axially by means of a cam 86 formed with a cam slot 87 to receive a roller 88 mounted on one end of a push rod 89.

The push rod 89 is mounted for axial movement in bearings 91 and engages one end of a connecting link 92 having its other end pivotally engaging a lever 93. The lever 93 is pivotally mounted on a bearing 94 secured to the frame 11 and has pins 96 mounted in its free end for engagement in a slot 97 formed in a collar 98 secured to the shaft 81.

The shaft 81 is rotated by means of a cam 103 mounted on the shaft 14. The cam is formed with a slot 104 to receive a roller 106 which is mounted on a lever 107 intermediate its ends.

The upper end of the lever is pivotally mounted on a bearing bracket 108 and its lower end is pivotally connected to a connecting link 109. The other end of the connecting link is pivotally connected to a gear segment 111 mounted for pivotal movement on a stud bearing 112 secured to the frame 11. The gear segment meshes with a pinion gear 113 which is keyed to the shaft 81 to prevent relative rotational movement and yet permit relative axial movement. A finger 114 is mounted on the frame 11 to engage in a slot 116 formed in the hub of the pinion gear. A compression spring 117 is mounted on the shaft 81 between the bearing 83 and the twister head 82; and a compression spring 118 is mounted on the shaft 81 between the bearing 84 and a lock collar 119 secured to the shaft. The twister head and the shaft 81 are formed with a slot 120 to receive the ends of the wire blank.

20 Hook forming mechanism

Referring now to Figs. 1 and 15 to 18, inclusive, I show a hook forming mechanism comprising a rocking frame 121 pivotally mounted on bearings 122 and formed with an actuating arm 123. 25 A hook forming arm 124 is journaled in the frame and provided with a crank arm 126 the end of which is pivotally connected to a stop member 127 slotted at 128 to receive a pin 129 mounted on a bracket 131 on the frame. An adjustment 30 screw 132 is mounted in the end of the stop member. A cable clamp 133, secured to the end of a cable 134, is also pivotally connected to the end of the crank arm 126; and a roller 136 is mounted on the end of the hook forming arm 124. Another hook forming arm 137 is journaled on the frame 121 and carries a roller 138 at its end to coat with the roller 136 to form the hook on the wire blank. The roller 138 is formed with grooves 139 to receive the end of the wire blank. A 40 sprocket gear 141 is secured to the arm 137.

The frame 121 is moved up and down by means of a cam 142 having a cam slot 143 adapted to receive a roller 144 mounted on a rocking lever 146 at its lower end. The lever 146 is pivotally mounted intermediate its ends on a bracket 147 mounted on the frame 11 and has its upper end engaging the actuating arm 123 through a connecting link 148. The length of the connecting link 148 may be adjusted by means of a turn-buckle 149. A wire positioning lever 151 is pivotally mounted on a bracket 152 provided on the cross frame member 34 and has its end pivotally connected to a connecting link 150 which, in turn, is pivotally connected to the frame 121. 55

The cable 134 is connected to one end of a sprocket chain 153 which extends around the sprocket 154, sprocket 141, and then has its other end connected to one end of a tension spring 155 connected to the frame member 27. The sprocket 154 is journaled in a bracket 156 pivotally mounted on the upper end of a rocking lever 157. This lever is pivotally mounted adjacent its center on a bracket 158 provided on the frame 11 and carries a roller 159 at its lower end for engagement with a cam 161 secured on the shaft 15.

Discharge mechanism

Referring now to Figs. 1 and 19, I show a discharge mechanism comprising a discharge plate 166 provided with a pair of vertically disposed kick-off rods 167 mounted in bearings 168 provided on the cross member 27. An arm 169 is also provided on the plate 166 to act with the rods 75

167 to remove the finished hangers from the form plate. Compression springs 171 are interposed between the plate 166 and the bearings 168 to yieldably resist a downward movement of the 5 discharge plate. A pair of rocker arms 172 and 173 are pivotally mounted on the cross member 27 and having their upper ends engaging the discharge plate while their lower ends are provided with rollers 174 and 176, respectively, for engagement with cams 177 and 178, respectively. The cams 177 and 178 are secured on the shafts 14 and 15, respectively.

In the operation of my machine, the wire blanks 42 are carried from their position on the 15 feed arms 41 to the form plate 26 by means of the feed carriage 29 which is actuated by the cam 38. The fingers 43, which form a V-shaped recess on the front of the feed carriage, serve to position the wire blanks against the form plate 20 where they are then formed and held against displacement by the forming lugs 44. The form plate and the forming lugs act to indent the trouser support bar 200 of the wire hanger 201. The feeding movement of the feed carriage also 25 causes the connecting links 48 to pivot the forming arms 46 about their axes to bend the wire blanks around the corners of the form plate 26. The tension spring 53 acts to pivot the forming arms 46 on the return stroke of the feeding carriage to take up the lost motion between the connecting links 48 and the pins 51.

While the wire blank is being held in position on the form plate by the forming lugs 44 and fingers 47 of the forming arms 46, the shoulder forming arms 56 and 57 are caused to move inwardly by their respective cams 66 and 67. The forming dies 68 and 69 act with the form plate to form the shoulder portion 202 of the hangers. The forward ends of the dies are provided with 35 positioning lugs 72 and 73 and slots 74 and 76 to accurately position the wire blank ends on the form plate 26 and act with the tongue 77 to bend the ends of the wire outwardly from the form plate for the twisting operation. The forming dies hold the wire blank in position on the 40 forming plate during the twisting operation, and the positioning lugs are arranged to carry the thrust of the wire ends during the twisting operation. As viewed in Fig. 10, the wire ends are 45 twisted in a clockwise direction in order that the lugs 72 and 73 will prevent displacement of the wire.

In the twisting operation to form the twist 203 in the hanger, the cam 86 acts through the push 55 rod 89, connecting link 92, lever 93, and shaft 81 to move the twister head 82 forward to receive the ends of the wire blank in the slot 120. The twister head 82 is then rotated by means of the cam 103 which acts through the lever 107, connecting link 109, gear segment 111, and pinion gear 113 mounted on the shaft 81. After the ends 60 of the wire have been twisted together, the twister head is moved rearwardly by the cam 86. The springs 117 and 118 serve to overcome the momentum of the moving parts.

The frame 121 of the hook forming mechanism is next lowered to form the hook 203 of the hanger. The frame 121 is actuated by the cam 142 acting through a rocking lever 146 and 70 connecting link 148. In forming the hook, the cam 161 acts through a rocking lever 157 to move the gear sprocket 154 away from the frame 121, thereby pulling the crank arm 126 until the stop screw 132 strikes the stop pin 129. The axis of 75 the roller 136 is then positioned in alignment

with the axis of the arm 137 and a further movement of the sprocket 154 causes the chain 153 to rotate the gear sprocket 141 which acts to bring the roller 138 around the roller 136 to form the hook. The rollers are then returned to their first position by means of the spring 130 which is under tension; and the frame is moved to its upper position by the cam 142.

The finished hanger is next discharged downwardly from the form plate 26 by the downward 10 movement of the fingers 167 and 169 actuated by the cams 177 and 178 through the rocking levers 172 and 173. The springs 171 act to return these parts to their first position.

While I have shown my invention in but one 15 form it is obvious to those skilled in the art that it is not so limited but is susceptible of various changes and modifications without departing from the spirit thereof; and I desire, therefore, that only such limitations shall be placed there- 20 upon as are imposed by the prior art.

I claim:

1. In a machine for forming wire garment hangers, the combination with a form plate, of a feed carriage for carrying wire blanks to the 25 form plate, forming arms pivotally mounted on the underside of the feed carriage, upturned fingers provided on the forming arms for engagement with the ends of the wire blanks, and connecting links having their inner ends pivotally 30 connected to the forming arms and their outer ends engaging the frame of the machine for actuating the forming arms to bend the wire blanks around the form plate.

2. In a machine for forming wire garment 35 hangers, the combination with a form plate, of a feed carriage for carrying wire blanks to the form plate, cam means for actuating said feed carriage, forming arms pivotally mounted on the feed carriage, connecting links having their one 40 ends connected to the forming arms and their other end engaging the frame of the machine, and tension spring means connecting the connecting links adjacent their ends connecting the forming arms.

3. A machine according to claim 2 in which, blank positioning fingers are provided on the feed carriage to position the blanks on the form plate.

4. A machine according to claim 2 in which, forming lugs are provided on the feed carriage to act with the form plate to form the wire blank.

5. In a machine for forming wire garment hangers, the combination with a form plate, of a pair of reciprocating dies to coact with the 55 form plate to form the shoulder portion of the wire hangers, and positioning lugs provided on the reciprocating dies for positioning the wire blank between the dies and the form plate during the shoulder forming operation.

6. A machine according to claim 5 in which, slots are formed at the base of the positioning lugs to receive the wire blank.

7. In a machine for forming wire garment hangers, a hook forming frame, a pair of arms 65 pivotally mounted on said frame, a roller provided on each arm for engagement with the wire blank to form a hook portion thereon, common means for moving said arms, and means for moving the hook forming frame into and out of operating position with respect to the wire blank.

8. In a machine for forming wire garment hangers, a hook forming frame, a pair of arms pivotally mounted on said frame, a roller provided on each of said arms for engagement with 75

the wire blanks to form a hook portion thereon, common means for moving said arms, means for moving the hook forming frame into and out of operating position with respect to the wire blank being formed, and means actuated by the hook forming frame for positioning the end of the wire blank with respect to the rollers prior to the hook forming operation.

9. In a machine for forming wire garment hangers, a hook forming frame, a pair of arms pivotally mounted on said frame, a roller provided on each of said arms for engagement with the wire blanks to form a hook portion thereon, a flexible connection engaging the arms to pivot same, cam actuated means for operating the flexible connection, adjustable stop means provided on one of said arms to limit the movement of same, means for moving the hook forming frame into and out of operating position with respect to the wire blank being formed, and means for positioning the end of the wire blank with respect to the rollers prior to the hook forming operation.

10. In a machine for forming wire garment hangers, the combination with a form plate, of a feed carriage for carrying wire blanks to the form plate, means for actuating said feed carriage, forming arms pivotally mounted on the feed carriage, upturned fingers provided on the forming arms for engagement with the ends of the wire blanks, connecting links having their inner ends pivotally connected to their respective forming arms and their outer ends engaging the frame of the machine, and tension spring means connecting the connecting links adjacent their inner ends.

11. In a machine for forming wire garment hangers, the combination with a form plate, of a feed carriage for carrying wire blanks to the form plate, means for actuating said feed carriage, forming arms pivotally mounted on the underside of the feed carriage, upturned fingers provided on the forming arms for engagement with the ends of the wire blanks, connecting links

having their inner ends pivotally connected to their respective forming arms and their outer ends engaging the frame of the machine, tension spring means connecting the connecting links adjacent their inner ends, and adjustment means for regulating the pivotal movement of the forming arms.

12. In a machine for forming wire garment hangers, the combination with a form plate secured to the frame of the machine, of a feed carriage for carrying wire blanks to the form plate, cam means for actuating said feed carriage, forming arms pivotally mounted on the underside of the feed carriage, upturned fingers provided on the forming arms for engagement with the ends of the wire blanks to bend same around the form plate, connecting links having their inner ends pivotally connected to their respective forming arms, means defining slots in the outer ends of the connecting links, pins mounted on the frame of the machine for engagement in their respective slots formed in the connecting links, and adjustment screws provided on the connecting links for engagement with said pins.

13. In a machine for forming wire garment hangers, the combination with a form plate secured to the frame of the machine, of a feed carriage for carrying wire blanks to the form plate, cam means for actuating said feed carriage, forming arms pivotally mounted on the feed carriage for bending the ends of the wire blanks around the form plate, connecting links having their inner ends pivotally connected to their respective forming arms and their outer ends engaging the frame of the machine, a pair of dies to coact with the form plate to form the shoulder portion of the wire hangers, cam means for moving said dies into and out of engagement with the form plate, and positioning lugs provided on the dies for positioning the wire blanks between the dies and the form plate during the shoulder forming operation.

FRANCIS B. TODD.
